W. H. PALMER

DEVICE FOR GUARDING TELLERS AND OTHER CUSTODIANS

Filed Feb. 12, 1923

FIG. 1

INVENTOR
W. H. Palmer.
BY E. J. Fetherstonhaugh
ATTORNEY

UNITED STATES PATENT OFFICE.

WILLIAM HENRY PALMER, OF MONTREAL, QUEBEC, CANADA.

DEVICE FOR GUARDING TELLERS AND OTHER CUSTODIANS.

Application filed February 12, 1923. Serial No. 618,732.

To all whom it may concern:

Be it known that I, WILLIAM HENRY PALMER, a subject of the King of Great Britain, and residing at 2044 Mance Street, 5 in the city of Montreal, in the Province of Quebec, in the Dominion of Canada, have invented a new and useful Improvement in a Device for Guarding Tellers and Other Custodians, of which the following is the 10 specification.

The invention relates to a device for guarding tellers and other custodians, as described in the present specification and shown in the accompanying drawings that form part 15 of the same.

The invention consists essentially of the novel features pointed out broadly and specifically in the claims for novelty following a description containing an explanation in 20 detail of an acceptable form of the invention.

The objects of the invention are to save the lives of employees and the property of the owners from the depredations of robbers, 25 particularly in banking institutions where daylight hold-ups are not by any means an uncommon occurrence; to facilitate the operation of such devices by the custodian of the valuables; to enable a teller in a bank 30 to obey the mandate of the would be robber without interfering with his means of operation; to eliminate losses by banks of considerable sums of money frequently 35 passed over the counter on the order of a gunman; to furnish a simple mechanism of few parts and not liable to get out of order; and generally to provide safety and assurance for those in charge of money or other valuable articles, which are ordinarily kept 40 in a public place.

In the drawings, Figure 1 is a rear elevation of the invention showing a portion of a bank counter and the teller's compartment and wicket.

Figure 2 is a sectional detail showing a fragmentary view of the counter and guard plate and adjacent parts.

Figure 3 is a detail showing the latch mechanism.

Figure 4 is a plan view showing the operating mechanism.

Like numerals of reference indicate corresponding parts in the various figures.

Referring to the drawings, the guard plate 1 preferably of steel is formed with 55 a lug 2 at each of its upper corners, which carry case hardened firing pins 3 securely soldered to said lugs that may be curled around the shanks of the pins, the heads of which project above the lugs.

The posts 4 and 5 of tubular form have the vertical slots 6 and 7 in which the plate 1 slides upwardly and downwardly, the lugs 2 being completely inside the posts to bring the heads of the firing pins 3 concentric with 60 the posts presuming that they are of circular shape in cross section though they may be of any suitable shape.

The posts 4 and 5 are mounted in the sockets 8 and 9 at their lower ends and these 70 sockets are secured to the raised platform 10 or to the floor as may be found more convenient.

The guns 11 are screwed in to the sleeves 75 12, joined by a cross rod at the upper ends of the posts 4 and 5, which sleeves are internally threaded for that purpose and these guns are formed with lower split ends 13 from the threaded body portion 14 and the tapering upper open ends 15 forming a vent 80 for the explosive gases.

The blank cartridges 16 are inserted in the split ends 13 and as the firing pins 3 strike them on the rapid upward movement 85 of the plate 1, the explosions occur, which thus act as an alarm for others present to mount guard and besides create sufficient consternation to materially assist in making a capture.

The plate 1 is bound on the upper end 90 with a brass strip forming at the upper side the horizontal flat surface 17 to close a slot and brought into the plate 1 on both sides and riveted under said flat top 17.

The lower end of the plate is bound with 95 the brass or copper strip 18 securely riveted thereto, and to this binding strip 18 the spring catch 19 is securely fastened, though

it may be secured directly to the plate 1. covered or there may be more than two posts 65 However, in order to have all surfaces and several guard plates if desired, but as smoothly covered it is better to have the a general rule one will be quite sufficient to binding strips of some material, which is frustate the intentions of the robber. 5 suitable for the purpose.

The helical cushion springs 20 are introduced into the posts 4 and 5 and are between the upper blocks 21 and lower blocks 22, which are circular in cross section or made 10 to suit the shape of the posts.

The lower blocks 22 are stopped by the blind nuts 23 and the upper blocks 21 freely slide in said posts and carry the plate 1 therewith, when said plate is released as explained hereinafter. 15

The latch bracket 24 is securely fastened to the platform 10 and is formed with a base 25, a vertical back guide plate 26 curved rearwardly at the upper end and the parallel 20 vertical plates 27 and 28 at each side of the latch pawl 29, which is pivotally supported in the angle pieces 30 and 31 rigid with the bracket 24 and is formed with the tooth 32 engaging the spring catch 19 in the lower- 25 most position of the plate 1, being held to that engagement by the spring 33.

The handles 34 are secured to the binding strip 18 and project downwardly therefrom in order that the plate 1 may be drawn 30 downwardly against the upward push of the springs 20 which are compressed in the lower ends of the columns 4 and 5 in order that the plate may be instantly shot to its upper position and supported in that position by 35 said springs, which are even then slightly compressed.

The pins 35 hanging by the chains 36 from the posts 4 and 5 are inserted in the holes 37 in said posts just above the lugs 2 40 in the lower position of the plate 1 to lock the plate 1 to its lower position after business hours.

The winch 38 is here shown as mounted on the platform 10 and rigidly secured there- 45 to, though it may be mounted at any convenient place and be operatively connected with the plate 1, but in the present form the cable 39 is wound on the drum 40 and connected to the plate 1 by the hook 41 at the 50 free end of the cable and by means of the crank handle 42 the plate 1 is drawn down and held by the pawl 43 and ratchet 44 of the winch, said pawl 43 being released by the foot lever 45 as customary in winch construction. The staple 46 in the post 4 for the hook 41 is situated to one side to keep the hook out of the way during the period that the guard plate is in active position.

The counter 47 of a banking or other in- 60 stitution is slotted at 48 just within the wicket 49 at the front of the cage 50 and the posts 4 and 5 project through the counter 47 behind the usual posts of the cage construction so that the teller or cashier is well

In the operation of this device, the plate 1 is set in its lower position and latched as described and ordinarily the business may be transacted as usual for there is nothing in sight and the slot in the counter is closed up by the brass binding strip and this may continue from day to day and year to year, yet all that time the teller or cashier is insured by this guard plate from injury, for 75 robbers are likely to avoid a place so guarded in order to save themselves, but in the event of a venturesome robber seeking money, where this guard is installed, the very second he points his revolver and demands money, the teller puts up his hands in surrender and at the same time touches the foot pedal of the latch pawl and the plate flies up in 80 the face of the robber, and if his gun is pointing inwardly it is knocked up in the air out of harms way, in any event the teller is shielded and a general alarm sounded by the blank cartridges, so that all are on the 85 alert and the robber's egress barred, for even the desperado as he must be, cannot help but be alarmed at the noise and confusion which he has caused, and as the bank officers are quite familiar with the apparatus, they know exactly what to do, in fact 90 they can be readily drilled to meet such occasions with calmness and intelligence, thereby making it impossible for robbers to carry out these daylight robberies in urban, 95 suburban or outlying places. 100

The guard plate herein described is shown as sliding up from below, as the most suitable form of the invention for general application, but conditions surrounding its installation may make other movements and construction desirable and electrical as well as mechanical operating means may be found very useful. 105

What I claim is:—

1. A teller's guard including a pair of spaced tubular guides having opposite slots, a shield movable vertically and having its side portion slidable in the guides, springs housed in the guides and located below the 115 shield for urging the same upwardly, hammers also slidable in the guide and mounted upon and carried by the shield, gun barrels mounted on the upper ends of the guides and forming stops for the shield and adapted to 120 receive blank cartridges to be exploded by the said hammers and means for setting and tripping the shield.

2. A teller's guard including spaced tubular guides, interiorly threaded sleeves fitted 125 on the upper ends of the guides, a cross rod connecting the sleeves, gun barrels movable throughout in the sleeves and extending into

the upper ends of the guides and adapted to receive blank cartridges, a shield slideable in the guides, springs housed in the guides and located below the shield for urging the same upwardly, hammers also slideable in the guides and mounted upon and carried by the shield for exploding the cartridges in the gun barrels, the latter forming stops for limiting the upward movement of the shield and means for setting and tripping the shields.

Signed at Montreal, Canada, this 25th day of January, 1923.

WILLIAM HENRY PALMER.
